FINGERNAIL ENAMEL COMPOSITION

Richard C. Peter, Parlin, N. J., assignor to E. I.
du Pont de Nemours & Company, Wilmington,
Del., a corporation of Delaware

No Drawing. Application July 8, 1937,
Serial No. 152,533

9 Claims. (Cl. 167—85)

This invention relates to fingernail enamel compositions which afford desirable improvements with respect to working properties, appearance and general durability.

5 Conventional fingernail enamels, especially those containing substantial quantities of cellulose nitrate are frequently characterized by an undesirable tendency to shrink during drying and to peel at the edge of the nail. Although it is evident that a maximum content of solid material at a workable viscosity is desired in order to provide adequate build and gloss, the concentration should not be so high that the flowing and drying qualities are impaired, yielding films 10 which are not sufficiently smooth to be practicable. Heretofore it has been the practice to restrict a nail enamel composition to substantially only cellulose nitrate as the solid body-producing material in order to obtain a quick-drying enamel, and as a result the important 15 properties of smoothness, flexibility and adhesion are sacrificed. Previously available fingernail enamels also possess an undesirable characteristic known as "bodying" which is a gradual thickening of the enamel by evaporation of the volatile ingredients, when the enamel is stored in poorly stoppered containers.

The teachings of the present invention provide for the production of a fingernail enamel wherein the several defects of such products previously available are eliminated.

It is an object of this invention to provide an enamel which when applied to fingernail and like surfaces affords a clear, smooth film of superior flexibility and adhesion. Another object is the provision of a fingernail enamel which is characterized by improved gloss and greater durability from the standpoint of abrasion resistance and freedom from cracking and peeling tendencies. Another object of the invention is the provision of a fingernail enamel which is characterized by absence of discoloration when exposed to light during storage in bottles or after application to the nail. A further object is the provision of a nail enamel composition which is stable with respect to dye-tinting and pigmentation. A still further object of the invention is the provision of a fingernail enamel composition which, when stored in poorly stoppered containers, does not substantially "body up" by an

increase in viscosity with evaporation of the volatile ingredients. Other objects will become apparent as the description of the invention proceeds.

These objects are accomplished by the utilization of a specific class of resins consisting of polymerization products of acrylic acid and acrylic acid derivatives in cellulose nitrate compositions as hereinafter more fully described.

By way of illustration but not by way of limitation, the following examples are given in accordance with the present invention:

Example 1

	Per cent
Cellulose nitrate.....	3.2 15
Denatured alcohol 2B.....	1.4
Butyl acetate.....	19.3
Ethyl acetate.....	19.3
Petroleum naphtha (boiling range 88— 131° C.).....	19.3 20
Toluol.....	19.3
Propyl methacrylate resin.....	15.0
Plasticizer.....	3.2
	100.0 25

Example 2

	Per cent
Cellulose nitrate.....	3.2
Denatured alcohol 2B.....	1.4 30
Butyl acetate.....	38.6
Petroleum naphtha (boiling range 105— 150° C.).....	38.6
Propyl methacrylate resin.....	15.0
Plasticizer.....	3.2 35
	100.0

The plasticizer used in the compositions of Examples 1 and 2 consisted of the phthalate ester of a mixture of synthetic higher alcohols 40 of four or more carbon atoms obtained during the synthesis of methanol as prepared by the catalytic hydrogenation of carbon monoxide at elevated temperatures and high pressures as described in U. S. Patent Nos. 1,820,417 and 1,844-45 857. The mixture of alcohols from which the ester is manufactured includes normal propanol, isobutanol, 2-methyl butanol-1, 3-methyl butanol-2, 2, 4-dimethyl pentanol-3, 3-methyl pentanol-2, 4-methyl hexanol-1, 4-methyl heptanol-2, 4-methyl heptanol-3, 4-methyl heptanol-4, 4-methyl heptanol-5, 4-methyl heptanol-6, 4-methyl heptanol-7, 4-methyl heptanol-8, 4-methyl heptanol-9, 4-methyl heptanol-10, 4-methyl heptanol-11, 4-methyl heptanol-12, 4-methyl heptanol-13, 4-methyl heptanol-14, 4-methyl heptanol-15, 4-methyl heptanol-16, 4-methyl heptanol-17, 4-methyl heptanol-18, 4-methyl heptanol-19, 4-methyl heptanol-20, 4-methyl heptanol-21, 4-methyl heptanol-22, 4-methyl heptanol-23, 4-methyl heptanol-24, 4-methyl heptanol-25, 4-methyl heptanol-26, 4-methyl heptanol-27, 4-methyl heptanol-28, 4-methyl heptanol-29, 4-methyl heptanol-30, 4-methyl heptanol-31, 4-methyl heptanol-32, 4-methyl heptanol-33, 4-methyl heptanol-34, 4-methyl heptanol-35, 4-methyl heptanol-36, 4-methyl heptanol-37, 4-methyl heptanol-38, 4-methyl heptanol-39, 4-methyl heptanol-40, 4-methyl heptanol-41, 4-methyl heptanol-42, 4-methyl heptanol-43, 4-methyl heptanol-44, 4-methyl heptanol-45, 4-methyl heptanol-46, 4-methyl heptanol-47, 4-methyl heptanol-48, 4-methyl heptanol-49, 4-methyl heptanol-50, 4-methyl heptanol-51, 4-methyl heptanol-52, 4-methyl heptanol-53, 4-methyl heptanol-54, 4-methyl heptanol-55, 4-methyl heptanol-56, 4-methyl heptanol-57, 4-methyl heptanol-58, 4-methyl heptanol-59, 4-methyl heptanol-60, 4-methyl heptanol-61, 4-methyl heptanol-62, 4-methyl heptanol-63, 4-methyl heptanol-64, 4-methyl heptanol-65, 4-methyl heptanol-66, 4-methyl heptanol-67, 4-methyl heptanol-68, 4-methyl heptanol-69, 4-methyl heptanol-70, 4-methyl heptanol-71, 4-methyl heptanol-72, 4-methyl heptanol-73, 4-methyl heptanol-74, 4-methyl heptanol-75, 4-methyl heptanol-76, 4-methyl heptanol-77, 4-methyl heptanol-78, 4-methyl heptanol-79, 4-methyl heptanol-80, 4-methyl heptanol-81, 4-methyl heptanol-82, 4-methyl heptanol-83, 4-methyl heptanol-84, 4-methyl heptanol-85, 4-methyl heptanol-86, 4-methyl heptanol-87, 4-methyl heptanol-88, 4-methyl heptanol-89, 4-methyl heptanol-90, 4-methyl heptanol-91, 4-methyl heptanol-92, 4-methyl heptanol-93, 4-methyl heptanol-94, 4-methyl heptanol-95, 4-methyl heptanol-96, 4-methyl heptanol-97, 4-methyl heptanol-98, 4-methyl heptanol-99, 4-methyl heptanol-100, 4-methyl heptanol-101, 4-methyl heptanol-102, 4-methyl heptanol-103, 4-methyl heptanol-104, 4-methyl heptanol-105, 4-methyl heptanol-106, 4-methyl heptanol-107, 4-methyl heptanol-108, 4-methyl heptanol-109, 4-methyl heptanol-110, 4-methyl heptanol-111, 4-methyl heptanol-112, 4-methyl heptanol-113, 4-methyl heptanol-114, 4-methyl heptanol-115, 4-methyl heptanol-116, 4-methyl heptanol-117, 4-methyl heptanol-118, 4-methyl heptanol-119, 4-methyl heptanol-120, 4-methyl heptanol-121, 4-methyl heptanol-122, 4-methyl heptanol-123, 4-methyl heptanol-124, 4-methyl heptanol-125, 4-methyl heptanol-126, 4-methyl heptanol-127, 4-methyl heptanol-128, 4-methyl heptanol-129, 4-methyl heptanol-130, 4-methyl heptanol-131, 4-methyl heptanol-132, 4-methyl heptanol-133, 4-methyl heptanol-134, 4-methyl heptanol-135, 4-methyl heptanol-136, 4-methyl heptanol-137, 4-methyl heptanol-138, 4-methyl heptanol-139, 4-methyl heptanol-140, 4-methyl heptanol-141, 4-methyl heptanol-142, 4-methyl heptanol-143, 4-methyl heptanol-144, 4-methyl heptanol-145, 4-methyl heptanol-146, 4-methyl heptanol-147, 4-methyl heptanol-148, 4-methyl heptanol-149, 4-methyl heptanol-150, 4-methyl heptanol-151, 4-methyl heptanol-152, 4-methyl heptanol-153, 4-methyl heptanol-154, 4-methyl heptanol-155, 4-methyl heptanol-156, 4-methyl heptanol-157, 4-methyl heptanol-158, 4-methyl heptanol-159, 4-methyl heptanol-160, 4-methyl heptanol-161, 4-methyl heptanol-162, 4-methyl heptanol-163, 4-methyl heptanol-164, 4-methyl heptanol-165, 4-methyl heptanol-166, 4-methyl heptanol-167, 4-methyl heptanol-168, 4-methyl heptanol-169, 4-methyl heptanol-170, 4-methyl heptanol-171, 4-methyl heptanol-172, 4-methyl heptanol-173, 4-methyl heptanol-174, 4-methyl heptanol-175, 4-methyl heptanol-176, 4-methyl heptanol-177, 4-methyl heptanol-178, 4-methyl heptanol-179, 4-methyl heptanol-180, 4-methyl heptanol-181, 4-methyl heptanol-182, 4-methyl heptanol-183, 4-methyl heptanol-184, 4-methyl heptanol-185, 4-methyl heptanol-186, 4-methyl heptanol-187, 4-methyl heptanol-188, 4-methyl heptanol-189, 4-methyl heptanol-190, 4-methyl heptanol-191, 4-methyl heptanol-192, 4-methyl heptanol-193, 4-methyl heptanol-194, 4-methyl heptanol-195, 4-methyl heptanol-196, 4-methyl heptanol-197, 4-methyl heptanol-198, 4-methyl heptanol-199, 4-methyl heptanol-200, 4-methyl heptanol-201, 4-methyl heptanol-202, 4-methyl heptanol-203, 4-methyl heptanol-204, 4-methyl heptanol-205, 4-methyl heptanol-206, 4-methyl heptanol-207, 4-methyl heptanol-208, 4-methyl heptanol-209, 4-methyl heptanol-210, 4-methyl heptanol-211, 4-methyl heptanol-212, 4-methyl heptanol-213, 4-methyl heptanol-214, 4-methyl heptanol-215, 4-methyl heptanol-216, 4-methyl heptanol-217, 4-methyl heptanol-218, 4-methyl heptanol-219, 4-methyl heptanol-220, 4-methyl heptanol-221, 4-methyl heptanol-222, 4-methyl heptanol-223, 4-methyl heptanol-224, 4-methyl heptanol-225, 4-methyl heptanol-226, 4-methyl heptanol-227, 4-methyl heptanol-228, 4-methyl heptanol-229, 4-methyl heptanol-230, 4-methyl heptanol-231, 4-methyl heptanol-232, 4-methyl heptanol-233, 4-methyl heptanol-234, 4-methyl heptanol-235, 4-methyl heptanol-236, 4-methyl heptanol-237, 4-methyl heptanol-238, 4-methyl heptanol-239, 4-methyl heptanol-240, 4-methyl heptanol-241, 4-methyl heptanol-242, 4-methyl heptanol-243, 4-methyl heptanol-244, 4-methyl heptanol-245, 4-methyl heptanol-246, 4-methyl heptanol-247, 4-methyl heptanol-248, 4-methyl heptanol-249, 4-methyl heptanol-250, 4-methyl heptanol-251, 4-methyl heptanol-252, 4-methyl heptanol-253, 4-methyl heptanol-254, 4-methyl heptanol-255, 4-methyl heptanol-256, 4-methyl heptanol-257, 4-methyl heptanol-258, 4-methyl heptanol-259, 4-methyl heptanol-260, 4-methyl heptanol-261, 4-methyl heptanol-262, 4-methyl heptanol-263, 4-methyl heptanol-264, 4-methyl heptanol-265, 4-methyl heptanol-266, 4-methyl heptanol-267, 4-methyl heptanol-268, 4-methyl heptanol-269, 4-methyl heptanol-270, 4-methyl heptanol-271, 4-methyl heptanol-272, 4-methyl heptanol-273, 4-methyl heptanol-274, 4-methyl heptanol-275, 4-methyl heptanol-276, 4-methyl heptanol-277, 4-methyl heptanol-278, 4-methyl heptanol-279, 4-methyl heptanol-280, 4-methyl heptanol-281, 4-methyl heptanol-282, 4-methyl heptanol-283, 4-methyl heptanol-284, 4-methyl heptanol-285, 4-methyl heptanol-286, 4-methyl heptanol-287, 4-methyl heptanol-288, 4-methyl heptanol-289, 4-methyl heptanol-290, 4-methyl heptanol-291, 4-methyl heptanol-292, 4-methyl heptanol-293, 4-methyl heptanol-294, 4-methyl heptanol-295, 4-methyl heptanol-296, 4-methyl heptanol-297, 4-methyl heptanol-298, 4-methyl heptanol-299, 4-methyl heptanol-300, 4-methyl heptanol-301, 4-methyl heptanol-302, 4-methyl heptanol-303, 4-methyl heptanol-304, 4-methyl heptanol-305, 4-methyl heptanol-306, 4-methyl heptanol-307, 4-methyl heptanol-308, 4-methyl heptanol-309, 4-methyl heptanol-310, 4-methyl heptanol-311, 4-methyl heptanol-312, 4-methyl heptanol-313, 4-methyl heptanol-314, 4-methyl heptanol-315, 4-methyl heptanol-316, 4-methyl heptanol-317, 4-methyl heptanol-318, 4-methyl heptanol-319, 4-methyl heptanol-320, 4-methyl heptanol-321, 4-methyl heptanol-322, 4-methyl heptanol-323, 4-methyl heptanol-324, 4-methyl heptanol-325, 4-methyl heptanol-326, 4-methyl heptanol-327, 4-methyl heptanol-328, 4-methyl heptanol-329, 4-methyl heptanol-330, 4-methyl heptanol-331, 4-methyl heptanol-332, 4-methyl heptanol-333, 4-methyl heptanol-334, 4-methyl heptanol-335, 4-methyl heptanol-336, 4-methyl heptanol-337, 4-methyl heptanol-338, 4-methyl heptanol-339, 4-methyl heptanol-340, 4-methyl heptanol-341, 4-methyl heptanol-342, 4-methyl heptanol-343, 4-methyl heptanol-344, 4-methyl heptanol-345, 4-methyl heptanol-346, 4-methyl heptanol-347, 4-methyl heptanol-348, 4-methyl heptanol-349, 4-methyl heptanol-350, 4-methyl heptanol-351, 4-methyl heptanol-352, 4-methyl heptanol-353, 4-methyl heptanol-354, 4-methyl heptanol-355, 4-methyl heptanol-356, 4-methyl heptanol-357, 4-methyl heptanol-358, 4-methyl heptanol-359, 4-methyl heptanol-360, 4-methyl heptanol-361, 4-methyl heptanol-362, 4-methyl heptanol-363, 4-methyl heptanol-364, 4-methyl heptanol-365, 4-methyl heptanol-366, 4-methyl heptanol-367, 4-methyl heptanol-368, 4-methyl heptanol-369, 4-methyl heptanol-370, 4-methyl heptanol-371, 4-methyl heptanol-372, 4-methyl heptanol-373, 4-methyl heptanol-374, 4-methyl heptanol-375, 4-methyl heptanol-376, 4-methyl heptanol-377, 4-methyl heptanol-378, 4-methyl heptanol-379, 4-methyl heptanol-380, 4-methyl heptanol-381, 4-methyl heptanol-382, 4-methyl heptanol-383, 4-methyl heptanol-384, 4-methyl heptanol-385, 4-methyl heptanol-386, 4-methyl heptanol-387, 4-methyl heptanol-388, 4-methyl heptanol-389, 4-methyl heptanol-390, 4-methyl heptanol-391, 4-methyl heptanol-392, 4-methyl heptanol-393, 4-methyl heptanol-394, 4-methyl heptanol-395, 4-methyl heptanol-396, 4-methyl heptanol-397, 4-methyl heptanol-398, 4-methyl heptanol-399, 4-methyl heptanol-400, 4-methyl heptanol-401, 4-methyl heptanol-402, 4-methyl heptanol-403, 4-methyl heptanol-404, 4-methyl heptanol-405, 4-methyl heptanol-406, 4-methyl heptanol-407, 4-methyl heptanol-408, 4-methyl heptanol-409, 4-methyl heptanol-410, 4-methyl heptanol-411, 4-methyl heptanol-412, 4-methyl heptanol-413, 4-methyl heptanol-414, 4-methyl heptanol-415, 4-methyl heptanol-416, 4-methyl heptanol-417, 4-methyl heptanol-418, 4-methyl heptanol-419, 4-methyl heptanol-420, 4-methyl heptanol-421, 4-methyl heptanol-422, 4-methyl heptanol-423, 4-methyl heptanol-424, 4-methyl heptanol-425, 4-methyl heptanol-426, 4-methyl heptanol-427, 4-methyl heptanol-428, 4-methyl heptanol-429, 4-methyl heptanol-430, 4-methyl heptanol-431, 4-methyl heptanol-432, 4-methyl heptanol-433, 4-methyl heptanol-434, 4-methyl heptanol-435, 4-methyl heptanol-436, 4-methyl heptanol-437, 4-methyl heptanol-438, 4-methyl heptanol-439, 4-methyl heptanol-440, 4-methyl heptanol-441, 4-methyl heptanol-442, 4-methyl heptanol-443, 4-methyl heptanol-444, 4-methyl heptanol-445, 4-methyl heptanol-446, 4-methyl heptanol-447, 4-methyl heptanol-448, 4-methyl heptanol-449, 4-methyl heptanol-450, 4-methyl heptanol-451, 4-methyl heptanol-452, 4-methyl heptanol-453, 4-methyl heptanol-454, 4-methyl heptanol-455, 4-methyl heptanol-456, 4-methyl heptanol-457, 4-methyl heptanol-458, 4-methyl heptanol-459, 4-methyl heptanol-460, 4-methyl heptanol-461, 4-methyl heptanol-462, 4-methyl heptanol-463, 4-methyl heptanol-464, 4-methyl heptanol-465, 4-methyl heptanol-466, 4-methyl heptanol-467, 4-methyl heptanol-468, 4-methyl heptanol-469, 4-methyl heptanol-470, 4-methyl heptanol-471, 4-methyl heptanol-472, 4-methyl heptanol-473, 4-methyl heptanol-474, 4-methyl heptanol-475, 4-methyl heptanol-476, 4-methyl heptanol-477, 4-methyl heptanol-478, 4-methyl heptanol-479, 4-methyl heptanol-480, 4-methyl heptanol-481, 4-methyl heptanol-482, 4-methyl heptanol-483, 4-methyl heptanol-484, 4-methyl heptanol-485, 4-methyl heptanol-486, 4-methyl heptanol-487, 4-methyl heptanol-488, 4-methyl heptanol-489, 4-methyl heptanol-490, 4-methyl heptanol-491, 4-methyl heptanol-492, 4-methyl heptanol-493, 4-methyl heptanol-494, 4-methyl heptanol-495, 4-methyl heptanol-496, 4-methyl heptanol-497, 4-methyl heptanol-498, 4-methyl heptanol-499, 4-methyl heptanol-500, 4-methyl heptanol-501, 4-methyl heptanol-502, 4-methyl heptanol-503, 4-methyl heptanol-504, 4-methyl heptanol-505, 4-methyl heptanol-506, 4-methyl heptanol-507, 4-methyl heptanol-508, 4-methyl heptanol-509, 4-methyl heptanol-510, 4-methyl heptanol-511, 4-methyl heptanol-512, 4-methyl heptanol-513, 4-methyl heptanol-514, 4-methyl heptanol-515, 4-methyl heptanol-516, 4-methyl heptanol-517, 4-methyl heptanol-518, 4-methyl heptanol-519, 4-methyl heptanol-520, 4-methyl heptanol-521, 4-methyl heptanol-522, 4-methyl heptanol-523, 4-methyl heptanol-524, 4-methyl heptanol-525, 4-methyl heptanol-526, 4-methyl heptanol-527, 4-methyl heptanol-528, 4-methyl heptanol-529, 4-methyl heptanol-530, 4-methyl heptanol-531, 4-methyl heptanol-532, 4-methyl heptanol-533, 4-methyl heptanol-534, 4-methyl heptanol-535, 4-methyl heptanol-536, 4-methyl heptanol-537, 4-methyl heptanol-538, 4-methyl heptanol-539, 4-methyl heptanol-540, 4-methyl heptanol-541, 4-methyl heptanol-542, 4-methyl heptanol-543, 4-methyl heptanol-544, 4-methyl heptanol-545, 4-methyl heptanol-546, 4-methyl heptanol-547, 4-methyl heptanol-548, 4-methyl heptanol-549, 4-methyl heptanol-550, 4-methyl heptanol-551, 4-methyl heptanol-552, 4-methyl heptanol-553, 4-methyl heptanol-554, 4-methyl heptanol-555, 4-methyl heptanol-556, 4-methyl heptanol-557, 4-methyl heptanol-558, 4-methyl heptanol-559, 4-methyl heptanol-560, 4-methyl heptanol-561, 4-methyl heptanol-562, 4-methyl heptanol-563, 4-methyl heptanol-564, 4-methyl heptanol-565, 4-methyl heptanol-566, 4-methyl heptanol-567, 4-methyl heptanol-568, 4-methyl heptanol-569, 4-methyl heptanol-570, 4-methyl heptanol-571, 4-methyl heptanol-572, 4-methyl heptanol-573, 4-methyl heptanol-574, 4-methyl heptanol-575, 4-methyl heptanol-576, 4-methyl heptanol-577, 4-methyl heptanol-578, 4-methyl heptanol-579, 4-methyl heptanol-580, 4-methyl heptanol-581, 4-methyl heptanol-582, 4-methyl heptanol-583, 4-methyl heptanol-584, 4-methyl heptanol-585, 4-methyl heptanol-586, 4-methyl heptanol-587, 4-methyl heptanol-588, 4-methyl heptanol-589, 4-methyl heptanol-590, 4-methyl heptanol-591, 4-methyl heptanol-592, 4-methyl heptanol-593, tanol-1, and higher alcohols. The phthalate ester may be conveniently manufactured by conventional esterification methods utilizing phthalic anhydride or it may be prepared by ester interchange as described in U. S. Patent No. 1,993,552. This plasticizer was found to have particular merit in the present compositions because of the superior water resistance afforded in its use.

Example 3

Example 3		Per cent
10	Cellulose nitrate	3.2
	Denatured alcohol 2B	1.4
	Butyl acetate	77.2
15	Propyl methacrylate resin	15.0
	Diamyl phthalate	3.2
		100.0

Example 4

	Per cent
20	
Cellulose nitrate	9.4
Denatured alcohol 2B	4.0
Isobutyl acetate	73.6
Isobutyl methacrylate resin	9.6
25 Tricresyl phosphate	3.4
	100.0

30 The viscosity characteristic of the cellulose nitrate used in the above examples is about 3 seconds as determined in accordance with procedure outlined in A. S. T. M. specifications D-301-33, Formula B. While a cellulose nitrate of about this viscosity characteristic is preferred, cellulose nitrates of somewhat higher or even lower viscosities may be utilized by suitable adjustments in the ratios of the other film-forming ingredients.

35

40 Denatured alcohol 2B, introduced by the alcohol-wet cellulose nitrate of commerce, is U. S. Internal Revenue Bureau formula which is composed of 100 gallons of 95% by volume ethyl alcohol to which has been added $\frac{1}{2}$ gallon of benzol. Other commercially available denatured alcohols are likewise suited for the present compositions
45 provided they do not impart a disagreeable odor to the product.

50 Examples 2, 3 and 4 are of particular importance since in these compositions, "bodying" tendencies which characterize previously available fingernail enamels are markedly reduced. The composition of Example 2 has the further advantage in that it may be applied directly over a dried film of a previously applied fingernail enamel without causing "lifting" of the first coating. The general utility of these and equivalent solvent and solvent-diluent compositions in fingernail enamels is disclosed in co-pending applications S. N. 152,532 and S. N. 152,534. The primary requirement for these ingredients is that 55 they have an evaporation rate approximately equal to that of butyl acetate.

The resin constituent of the new compositions is preferably a polymerization product of propyl, butyl or isobutyl methacrylate, although the higher aliphatic and alicyclic alcohol polymers, such as hexyl, heptyl, octyl, lauryl, cetyl, allyl, methoxyethanol, cyclohexyl and methoxycyclohexyl alcohol esters of methacrylic acid, and the corresponding ester polymers of acrylic acid are likewise suited. In general, polymerized esters of an acrylic acid, the acid being represented by the general formula

where R is hydrogen or an alkyl radical, may be used.

The methyl and ethyl methacrylate compounds are relatively impractical for use in the cellulose nitrate compositions of the present invention because of the excessively high viscosities which characterize these combinations. In addition, the degree of wear and abrasion resistance secured from compositions based on these resins is not as great as when the higher alcohol esters are employed. 5 10

The preparation of monomeric acrylic acid esters is described in the co-pending application of D. J. Loder, Serial No. 593,411. The polymerization of the esters is effected by well-known methods, as for instance with the aid of light, heat or a suitable catalyst, such as an organic peroxide. 15

Other plasticizers which may be employed in the compositions of this invention include di-
butyl, dihexyl, diheptyl, dioctyl phthalates, tri-
butyl phosphate, dibutyl tartrate, methoxy ethyl
phthalate, etc. 20

The solvent vehicle of the present invention consists of not less than 75 per cent of the preferred composition, and is preferably selected from a group of solvents of medium volatility which will produce a coating of adequate smoothness, free from turbidity and coloration. High boiling solvents are eliminated in the preparation of this type of nail enamel because of their slow rate of evaporation. The more volatile solvents are generally not preferred due to their more rapid evaporation causing an "orange peel" surface.

Optimum conditions for securing the outstanding qualities which characterize this improved nail enamel are obtained when the cellulose nitrate-resin-plasticizer ratios are within the range of 10-10-4 and 10-50-10 parts by weight, although satisfactory results in build, clarity, gloss and durability are also obtained somewhat beyond the upper limit of the resin proportion shown. Also some improvements are apparent when the resin proportion is reduced to a ratio of 10-5-2 or even lower, but the range indicated above is much preferred. 40 45

The resins of the present invention have been found to be of particular merit in fingernail enamel compositions. They do not materially increase the viscosity of the enamel, and hence permit the building up of a high solids content which in turn allows a lower concentration of cellulose nitrate thereby eliminating undesirable shrinkage tendencies and separation of the film from the fingernail surface. The tendency of "bodying" when stored in poorly stoppered containers such as is experienced with the conventional fingernail enamels, is substantially reduced when the preferred solvent compositions as previously indicated are employed.

The several ingredients of fingernail enamel compositions of the invention are thoroughly and uniformly blended by ordinary mixing processes. The final compositions flow freely and are easily applied to the finger or toe nail with a soft brush. On drying a clear, odorless, transparent film results. The coating does not discolor during exposure and wear. Dyes or pigments which are commonly incorporated in nail enamels are unaffected by the improved vehicle. The enamels afford excellent adhesion, and are remarkably resistant to soapy water, alkali, marring and scratching. These durable compositions are characterized by extraordinarily high solids for 75

a given viscosity, thus providing the requisite gloss and build with one application.

It is apparent that many widely different embodiments of this invention may be made without departing from the spirit and scope thereof; and, therefore, it is not intended to be limited except as indicated in the appended claims.

I claim:

1. A fingernail enamel composition comprising cellulose nitrate, a plasticizer and a polymerized organic derivative of an acrylic acid selected from the group consisting of aliphatic and alicyclic esters of an acrylic acid.

2. Composition of claim 1 in which the acrylic acid is represented by the general formula

20 where R is an alkyl radical.

3. A fingernail enamel composition comprising cellulose nitrate, a plasticizer and a polymerized ester of methacrylic acid derived from a straight chain alcohol containing more than 2 carbon atoms.

25 4. Composition of claim 3 in which the methacrylate polymer is derived from propyl alcohol.

5. Composition of claim 3 in which the methacrylate polymer is derived from isobutyl alcohol.

30 6. Composition of claim 1 in which the ratio of cellulose nitrate to resin polymer to plasticizer lies between 10-50-10 and 10-5-2 parts by weight.

7. A fingernail enamel composition consisting of cellulose nitrate, a plasticizer, a polymerized organic derivative of an acrylic acid selected from the group consisting of aliphatic and alicyclic esters of an acrylic acid and a liquid volatile vehicle consisting substantially of a liquid volatile solvent having an evaporation rate approximately equal to that of butyl acetate.

5 8. A fingernail enamel composition consisting of cellulose nitrate, a plasticizer, a polymerized 10 organic derivative of an acrylic acid selected from the group consisting of aliphatic and alicyclic esters of an acrylic acid and a liquid volatile vehicle consisting substantially of a solvent-diluent mixture having an evaporation rate approximate- 15 ly equal to that of butyl acetate.

9. A fingernail enamel having approximately the following composition:

	Per cent
Cellulose nitrate	3.2 20
Denatured alcohol	1.4
Butyl acetate	38.6
Petroleum naphtha	38.6
Resin (propyl methacrylate polymer)	15.0
Plasticizer (phthalate ester of a mixture of higher synthetic alcohols obtained by catalytic hydrogenation of carbon monoxide)	25 3.2
	100.0 30

RICHARD C. PETER.
